(57) **CLAIM**

The ornamental design for a playground balance pod, as shown and described.

DESCRIPTION

FIG. 1 is a perspective view of the playground balance pod design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is an alternative perspective view showing the playground balance pod in a different environment.

The phantom line showing of environment and utilitarian skid resistance on the surface of the balance pod designs, is for illustrative purposes only.
